United States Patent Office.

WILLIAM STEVENS, OF BLOOMINGTON, ILLINOIS.

Letters Patent No. 69,505, dated October 1, 1867.

IMPROVEMENT IN FURNACES.

The Schedule referred to in these Letters Patent and making part of the same.

TO ALL WHOM IT MAY CONCERN:

Be it known that I, WILLIAM STEVENS, of Bloomington, in the county of McLean, and in the State of Illinois, have invented certain new and useful improvements in Device for Consuming the Smoke and Gas arising from Steam Boilers; and do hereby declare that the following is a full, clear, and exact description thereof, reference being had to the accompanying drawings and to the letters of reference marked thereon, making a part of this specification.

In the annexed drawings, A A represent the two walls of a furnace or boiler. These walls are made of brick, in the ordinary manner, with suitable bearings for the boiler. B represents the doors at the front of the fire, while B' represents the doors in front of the ash-pit. Extending from side to side of the wall, between the doors B and B', is a hollow tube, which is open at both ends. Opening into this tube is a series of small pipes, i i i, which are placed, one under each grate, and extend the whole length of the furnace, as seen in fig. 1. D represents a narrow chamber, formed at the rear end of the furnace, between the walls C C', and into which the small tubes i i open. The top of this chamber has a curved metal plate, G, with perforations x x, as seen in fig. 2. K represents a pipe, which opens into one side of this chamber, and which admits exhaust steam. The fire is built upon the grates, within the furnace, above the tubes i i, and cold air passing into the tube, E, at both sides, is conducted into the pipes i i, and heated in going through the said pipes, entering the chamber D. The steam from the pipe k, coming in upon the hot air in the chamber, passes up in jets through the perforated plate G, and intersects the flame from the furnace at this point, and consumes the smoke and gas arising therefrom.

Having thus fully described my invention, what I claim as new, and desire to secure by Letters Patent, is—

1. The tube E, and pipes i i, arranged in the manner as specified, and used for the purposes set forth.
2. The arrangement of the chamber D and perforated plate G, in combination with the tube E and pipes i i i, in the manner and for the purposes specified.

In testimony that I claim the foregoing I have hereunto set my hand this 21st day of March, 1867.

WILLIAM STEVENS.
